Inventor
John J. Allison

Attorney
F. M. Land

UNITED STATES PATENT OFFICE.

JOHN J. ALLISON, OF SMETHPORT, PENNSYLVANIA.

CONDUIT-MAKING MACHINE.

Application filed March 31, 1923. Serial No. 629,064.

To all whom it may concern:

Be it known that I, JOHN J. ALLISON, a citizen of the United States, residing at Smethport, in the county of McKean and State of Pennsylvania, have invented new and useful Improvements in Conduit-Making Machines, of which the following is a specification:

The invention is designed to improve the action of conduit making machines so that the trimming of the end of the conduit may be accomplished coincidentally with the forming of the material. In carrying out the invention the material is extruded in the usual manner and as it is extruded the inner edge of the end is bevelled in the usual manner of conduits so that when a length sufficient for a length of conduit has been extruded it may be severed and the end so trimmed will be complete.

The invention is illustrated in the accompanying drawings as follows:

Fig. 1 shows a side elevation of the machine.

25 Fig. 2 a plan view of the die plate.

Fig. 3 a plan view of the yielding platform.

Fig. 4 a section on the line 4-4 in Fig. 3.

Fig. 5 an enlarged view of the mounting 30 for the trimmer.

1 marks the steam cylinder, 2 the valve controlling the steam cylinder, 3 the operating lever, 4 a head on which the steam cylinder is mounted, 5 posts carrying the head 4; 6 a piston rod extending from the steam cylinder, 7 a plunger on the piston rod, 8 a mud chamber, 9 the die head of the mud chamber, 10 shoulders on the posts 5 on which the head 9 rests, 11 the mud passages,

40 12 the die plate secured to the head 9 and having the die openings 13 extending from the passages 11, 14 the die cores holding the dies 15, 15^a a frame carrying the die cores 14, 15^b posts carrying the frame, and 16 adjusting plates for adjusting the flow from the dies. These parts are or may be of usual construction. Some of the plates, particularly the adjusting plates form the subject matter of a companion application #629,065.

50 A platform 17 is arranged in alinement with the die openings 13 and receives the extruded material in the usual manner. As shown there are four dies and provision for receiving four tubes with each operation. The platform 17 is mounted on the posts 18 which extend to a head 19 carried by a plunger 20.

The head 19 is guided by the posts 5 and is balanced through a cable 19^a extending through the blocks 19^b over the pulleys 19^c on the shaft 19^d to the weights 19^e. It will be noted that the pulleys 19^c at the two sides of the machine are locked on the shaft 19^d so as to tend to keep these parts in parallel.

Guide plates 21 are arranged on the platform 17 in position to receive the ends of the extruded material as indicated by A. The platform has an extension lip 22 extending outwardly from the guide plates 21. With the material received in this socket and in position it is trimmed by a wire cutter 23. This wire cutter is secured at the lower end on a hook 24 and at the upper end on a hook 25. The hook 25 is carried by a screw 26 which may be adjusted by a nut 27. The nut 27 is carried by a post 28 secured on a sliding bar 29 by a set screw 30. The hook 24 is also secured on this bar. The wire, as will be seen, is given an inclination and will trim the end of the material to the bevel desired.

The mounting and operation of the cutter is as follows: A fork 31 is arranged on the end of the bar 29 and a guide pulley 32 is journaled in this fork and operates against a guide track 33 which is secured to the under side of the platform. The bar 29 is slidingly mounted in an opening 34 in a head 35. A block 36 is secured on the bar by a screw 37 and guide plates 38 are arranged at each side of the block 36 and secured to the head by a screw 39. The guides 38 are connected at 40 and the bar extends through this connection. A spring 41 is arranged around the bar and between the block 36 and the end 40 and tends to move the block toward the head and as a result tends to move the end of the bar, carrying the post 28 and hook 24 outwardly in a radial direction. This holds the guide roller 32 against the track 33 and in consequence the bar follows the contour of the track and the contour of the track has the contour of the end of the tube as it is extruded from the dies. Consequently the cutter 23 follows the contour of the end of the tube and trims the tube. Ordinarily the conduit is about the form shown, nearly rectangular in shape, with a slightly rounded corner and the guide as shown has this form, the cutter following this form and trimming the tube.

I prefer to accomplish the trimming as the platform advances so that at the com-

pletion of the movement of the platform the trimming is also completed. Each head 35 is carried by a shaft 42. The shaft 42 is mounted in a bearing 43. The bearing 43 is arranged in a post 44 on the head 19. A gear 45 is fixed on the shaft 42 and meshes with a gear 46. It will be understood that each of the gears 45 mesh with a single gear 46 which is at the center of the platform. 10 The gear 46 is mounted on a shaft 47. The shaft 47 is carried in bearings 48 and 49. A beveled gear 50 is secured to the gear 46. The beveled gear 50 meshes with a beveled gear 51. The gear 51 is fixed on a shaft 52. 15 The shaft 52 is journaled in bearings 53 on the head 19. A spool 54 is fixed on the shaft 52. A cable 55 is wound around the spool and secured at one end to the head 9 and is provided with a weight 56 at its opposite end.

It will readily be seen that as the platform 17 is raised and lowered the cable will wind on and off the spool 54, thus rotating it so that with the platform in its upper position and the material A extruded from the dies on the platform immediately the platform is pressed downwardly by the material as it is extruded the trimmers rotate preferably making two rotations in the downward movement so as to completely trim the end of the tube with the bevel or shape desired.

Upon the completion of the downward movement the tube is severed in the usual manner by a cutter (not shown).

What I claim as new is:—

1. In a conduit making machine, the combination of a mud chamber; a die through which the material is extruded in tubular form; a yielding platform receiving the formed material as extruded; and means trimming the end of the formed tube resting on the platform.

2. In a conduit making machine, the combination of a mud chamber; a die through which the material is extruded in tubular form; a yielding platform receiving the formed material as extruded; and means carried by the platform trimming the end of the formed tube resting on the platform.

3. In a conduit making machine, the combination of a mud chamber; a die through which the material is extruded in tubular form; a yielding platform receiving the formed material as extruded; and means carried by the platform and actuated as the platform advances trimming the end of the formed tube resting on the platform.

4. In a conduit making machine, the combination of a mud chamber; a die through which the material is extruded in tubular form; a yielding platform receiving the formed material as extruded; and means carried by the platform and actuated as the platform advances trimming the end of the

formed tube resting on the platform by the movement of the platform.

5. In a conduit making machine, the combination of a mud chamber; a plurality of dies through which the material is extruded in tubular form; a yielding platform receiving a plurality of formed tubes as extruded; and means carried by the platform trimming the end of the formed tubes resting on the platform.

6. In a conduit making machine, the combination of a mud chamber; a plurality of dies through which the material is extruded in tubular form; a yielding platform receiving a plurality of formed tubes as extruded; and means carried by the platform and actuated as the platform yields for trimming the ends of the formed tubes resting on the platform.

7. In a conduit making machine, the combination of a mud chamber; a die through which the material is extruded in tubular form; a yielding platform receiving the formed material as extruded; and a rotary cutter trimming the end of the formed tube resting on the platform.

8. In a conduit making machine, the combination of a mud chamber; a die through which the material is extruded in tubular form; a yielding platform receiving the formed material as extruded; and a rotary cutter carried by the platform trimming the end of the formed tube resting on the platform.

9. In a conduit making machine, the combination of a mud chamber; a die through which the material is extruded in tubular form; a yielding platform receiving the formed material as extruded; and a rotary cutter carried by the platform and actuated as the platform yields trimming the end of the formed tube resting on the platform.

10. In a conduit making machine, the combination of a mud chamber; a die through which the material is extruded in tubular form; a yielding platform receiving the formed material as extruded; a rotary cutter trimming the end of the formed tube resting on the platform; and a guide on the platform controlling the path of the cutter.

11. In a conduit making machine, the combination of a mud chamber; a die through which the material is extruded in tubular form; a yielding platform receiving the formed material as extruded; a rotary cutter trimming the end of the formed tube resting on the platform; a radially movable mounting for the cutter; and a guide controlling the path of the cutter.

12. In a conduit making machine, the combination of a mud chamber; a die through which the material is extruded in tubular form; a yielding platform receiving the formed material as extruded; a rotary

cutter trimming the end of the formed tube resting on the platform; a radially movable mounting for the cutter; a spring yieldingly moving the cutter in one direction; and
5 a guide track against which the cutter is moved by the spring.

13. In a conduit making machine, the combination of a mud chamber; a die through which the material is extruded in
10 tubular form; a yielding platform receiving the formed material as extruded; a rotary cutter trimming the end of the formed tube resting on the platform; a radially movable bar on which the cutter is mounted;
15 a head in which the bar is mounted; a shaft carrying the head; a guide carried by the head; a spring acting on the bar; and a guide track against which the bar is pressed.

20 14. In a conduit making machine, the combination of a mud chamber; a die through which the material is extruded in tubular form; a yielding platform receiving the formed material as extruded; a rotary cutter trimming the end of the formed tube resting on the platform; and a driving connection carried by the platform for the cutter comprising a spool, and a cable wound on the spool, said cable having its ends sta-
25 tionary.

30 15. In a conduit making machine, the combination of a mud chamber; a die through which the material is extruded in tubular form; a yielding platform receiv-
35 ing the formed material as extruded; a ro-

tary cutter trimming the end of the formed tube resting on the platform; and a driving connection carried by the platform for the cutter comprising a spool, and a cable wound on the spool, said cable having its 40 ends stationary and the lower end weighted.

16. In a conduit making machine, the combination of a mud chamber; dies through which the material is extruded from the mud chamber; a yielding platform 45 having a plurality of faces receiving the material as it is extruded; a plurality of rotary cutters mounted on the platform and trimming the end of the material as the platform advances; mountings for the cutters; gears on the mountings; a central gear driving the plurality of mountings; and a driving means for the central gear.

17. In a conduit making machine, the combination of a mud chamber; dies 55 through which the material is extruded from the mud chamber; a yielding platform having a plurality of faces receiving the material as it is extruded; a plurality of rotary cutters mounted on the platform and 60 trimming the end of the material as the platform advances; mountings for the cutters; gears on the mountings; a central gear driving the plurality of mountings; and a driving means for the central gear comprising 65 devices actuated by the movement of the platform.

In testimony whereof I have hereunto set my hand.

JOHN J. ALLISON.
